PROTECTIVE COOLING SYSTEM FOR
THERMIONIC APPARATUSMarcus A. Acheson, Schenectady, N. Y., assignor
to General Electric Company, a corporation of
New York

Application December 27, 1928. Serial No. 328,819

3 Claims. (Cl. 250—27.5)

The present invention relates to a power tube equipment, more particularly to a protective system for ensuring the application of a cooling fluid to the various heated parts of a thermionic device during operation.

In the operation of transmitter tube apparatus, it has been found that when the stem, through which the filament leading-in conductors pass, tends to become heated, fissures may form in the pinch seal and the vacuum fail. This condition is due, in some measure, to the fact that the heat produced in these conductors by current flow is more or less confined by the cylindrical glass wall forming the reentrant stem and also due to the heat radiated by the incandescent portion of the cathode. It is therefore necessary to provide a means for cooling the pinch seal and in the past it has been customary to insert a rubber tubing into the reentrant stem in such a manner that a cooling fluid may be directed against the leading-in conductors and the pinch seal. However, as a practical matter, the detail of inserting the tubing may be neglected at the time the filament circuit is initially energized whereupon the heat generated by the large filament current causes the seal to become unduly hot.

Among the objects of the invention is to provide a means which will ensure the insertion of the tubing into the reentrant stem at the time the tube is operated, thereby to provide a positive protection of the stem against high temperature, and, in general, to assure the maintenance of certain portions of the envelope, subject to considerable heat during operation, relatively cool.

For carrying out the objects of this invention, I have devised an adaptor which directs a supply of cooling fluid to the heated parts simultaneously with the operation of energizing the device. The adaptor may take the form, in brief, of a combined air supply conduit and an electrical switch which is connected in the filament energizing circuit. When the filament circuit is closed by moving the adaptor into position, connection is also made with an air supply manifold which serves to provide the cooling medium.

Other objects and features will be apparent as the specification is perused in connection with the accompanying drawing in which Fig. 1 illustrates the side elevational view of a power tube to which the invention has particular application; Fig. 2 is an enlarged elevational view of the adaptor which forms the subject matter of the present invention; Fig. 3 is a view partly in cross section of the tube, filament leads and reentrant

stem, also showing the adaptor in detail while Fig. 4 is a diagram of a preferred form of electrical circuit for energizing the filament.

In the drawing, numeral 1 designates a glass portion of an evacuated envelope, the lower end of which terminates in a cylindrical anode 2 and the upper end in a reentrant glass portion 3. Within the anode there is mounted, in any suitable manner, a rectilinear filamentary cathode (not shown) and a cylindrical grid or electrostatic control member (not shown) positioned concentrically between the cathode and the anode. The upper end of the filament is secured in position by means of two conductors 4, 4 which are sealed in the press of the reentrant stem 3. The grid member is rigidly mounted in the interior of the anode by means of a grid clamp 5 which embraces a glass skirt portion 6 forming an extension of the reentrant stem 3. The leading-in conductors for the filament terminate in the flexible cables 7, 7 to which are connected metallic coupling members 8, 8. The leading-in conductor for the grid preferably comprises a flexible strip 9 secured to the grid clamp and is usually taken from the side of the envelope through a tubulation 10. In order rigidly to space the filament conductors from one another and to remove the mechanical stress at the press seal due to the lever effect of the conductors at this point, there is provided a metallic cap 11 which fits over the upper end of the envelope and is secured thereto in any suitable manner, for example by means of a cement 12. The cap 11 contains a plurality of symmetrically spaced apertures within which bushings 13 of insulating material are fitted; these bushings receive the filament cables 7, 7 as shown. The cap also contains other apertures, of which one may be employed to receive a rigid tubing 14 of insulating material such as bakelite, which tubing is employed for the purpose of directing a cooling fluid against the lower portions of the filament conductors, the pinch seal and other heated parts; the remaining apertures may serve as a means of egress for the cooling fluid contained in the stem. The tubing 14 is secured rigidly to the cap member preferably by means of screw threads and a nut 15. The upper end of the tubing is carried through the aperture to form an extension which terminates in a metallic ferrule or collar 16. The adaptor proper consists in an annular nozzle member 17, preferably of bakelite, counterbored to a limited depth snugly to receive the ferrule which is fitted about the upright tubing 14. The

adaptor preferably tapers off to a size as will wedge tightly within the flexible hose 18 which communicates with a source of cooling fluid (not shown) preferably under pressure. As explained hereinbefore, simultaneously with positioning the nozzle member on the tubing 14, it is desired to energize the filament circuit and for this purpose there is provided two contact strips 19, 19 preferably of copper, arranged diametrically across the counterbore and held in place by two terminals 20, 20. The terminals extend radially into the bore a distance to provide a stop or seat for the upper surface of the ferrule when the adaptor is moved into operating position. The latter position is clearly shown in Fig. 3 while the non-operating or inactive position of the adaptor is illustrated in Fig. 2.

One form of an electrical circuit arrangement which operates satisfactorily with the adaptor is shown in Fig. 4. The terminals 20, 20 are connected serially in a circuit which includes a source of electromotive force 21 and an electromagnet 22. The core 23 of the latter is attached to an armature 24 which makes and breaks a connection with a contact 25. The armature and contact are connected in a circuit preferably energized by a source 27 of alternating current preferably of commercial frequency and voltage, the latter being stepped down to a suitable voltage by a transformer 26. The filament leads 7, 7 are connected across the secondary of the transformer, as shown. It will be evident that when the adaptor 17 is placed in position about the ferrule 16, the latter serves to complete the circuit through the terminals 20, 20 and battery 21, thus energizing the electromagnet. The armature 24 is then pulled up to complete circuit through the transformer 26 and the source of alternating current with the result that the filament is energized. The adaptor, in addition to causing the energization of the filament as described, also provides a connecting passage between the air supply hose 18 and the rigid tubing 14 positioned within the reentrant stem 3. Consequently, a supply of cooling fluid is directed against the stem and filament leads simultaneously with the act of energizing the filament. When the adaptor is removed manually to break the filament circuit, the continuity of the air passage is also broken. An important advantage in rigidly fixing the tubing 14 to the cap 11 resides in the fact that the presence of such a tubing is assured and the detail of inserting the member into the stem may be entirely dispensed with after the cap has been positioned on the envelope.

What I claim as new and desire to secure by Letters Patent of the United States, is:

1. Thermionic apparatus comprising the combination of an evacuated envelope containing an electrode adapted to be energized, said envelope being subjected to heating during the operation of the apparatus, a conduit for directing a cooling fluid against the heated portions of said envelope, said conduit being rigidly affixed in position, an adaptor of annular form which is normally entirely separate from said conduit, said adaptor communicating at one end with a source of cooling fluid and at the other end is adapted to be placed in register with the opening of said conduit for supplying the conduit with cooling fluid and means whereby the adaptor also operates to control the energization of the electrode adapted to be energized. 80

90

2. Thermionic apparatus comprising the combination of an evacuated envelope containing an electrode adapted to be energized, said envelope being subjected to heating during the operation of the apparatus, a conduit for directing a cooling fluid toward the heated portions of said envelope, said conduit being rigidly affixed in position with respect to said envelope, an adaptor of annular form which is normally entirely separate from said conduit, said adaptor being flexibly joined at one end to a source of cooling fluid and at the other end is adapted to be placed in register with the opening of said conduit for supplying the conduit with cooling fluid and means whereby the adaptor also operates to control the energization of the electrode adapted to be energized, said means comprising an electrical contact making device associated with the adaptor. 95

100

110

115

3. Thermionic apparatus comprising the combination of an evacuated envelope having a re-entrant stem and containing an electrode adapted to be energized whereby the stem is subjected to heating during the operation of the apparatus, means for maintaining the stem relatively cool, said means comprising a conduit of insulating material positioned within the stem and terminating at the end remote from the stem in a metallic member, an adaptor having an aperture adapted to embrace the metallic member when the adaptor is in an operating position, a source of cooling fluid associated with the aperture, said adaptor being provided with contacts disposed on opposite sides thereof, the contacts being adapted to be connected in a circuit which controls an electrode energizing circuit so that when the adaptor is placed on the metallic member in an operating position, a circuit is completed through the said contacts thereby to cause energization of the electrode and to cause cooling fluid to flow from said source through the conduit thereby to maintain the stem relatively cool. 120
